2 SHEETS—SHEET 2.

UNITED STATES PATENT OFFICE.

WILLIAM S. LOUCEE, OF ROCHESTER, NEW HAMPSHIRE, ASSIGNOR TO J. SPAULDING & SONS CO., OF ROCHESTER, NEW HAMPSHIRE, A COPARTNERSHIP COMPRISING EMMA C. SPAULDING AND MARION L. SPAULDING, BOTH OF BOSTON, MASSACHUSETTS, ROLAND H. SPAULDING AND HUNTLEY N. SPAULDING, BOTH OF ROCHESTER, NEW HAMPSHIRE, AND LEON C. SPAULDING, OF BUFFALO, NEW YORK.

CRIMPING OR CORRUGATING MACHINE.

1,160,732.

Specification of Letters Patent. Patented Nov. 16, 1915.

Application filed May 11, 1914. Serial No. 837,655.

To all whom it may concern:

Be it known that I, WILLIAM S. LOUCEE, a citizen of the United States, residing in Rochester, in the county of Strafford and 5 State of New Hampshire, have invented an Improvement in Crimping or Corrugating Machines, of which the following description, in connection with the accompanying drawings, is a specification, like characters 10 on the drawings representing like parts.

This invention relates to a crimping or corrugating machine, which is especially designed and adapted for crimping or corrugating the lip of a channeled inner sole.

15 The invention has for its object to provide a simple, efficient and inexpensive machine, which is particularly useful for providing the lip of the inner sole with a corrugation or crimp, which is deeper at the free edge 20 of the lip and diminishes to substantially nothing near the bottom of the lip, whereby an inner sole of substantially non-compressible material may be provided with a lip, which extends substantially at right angles

25 to the body portion of the inner sole. For this purpose, the machine is provided with coöperating rotatable beveled crimping members, having teeth or crimping edges, which are of greater depth at one surface 30 than at the other of said members to form tapering teeth, so that the work passed between the intermeshing members may be provided with a tapering corrugation or crimp, as will be described. Provision is

35 made for driving the crimping members in unison, and for supporting the work while being crimped. Provision is also made for compensating for different thicknesses of stock, as will be described.

40 The particular features of the invention will be pointed out in the claims at the end of this specification.

Figure 1 is a side elevation of a machine embodying this invention. Fig. 2, a horizontal section on the line 2—2, Fig. 1. Fig. 45 3, a vertical section on the line 3—3, Fig. 2. Fig. 4, a detail in section of the crimping members shown in Fig. 1. Fig. 5, a modification to be referred to, and Fig. 6, an elevation of a portion of a lip provided with corrugations or crimps made with the machine herein shown.

Referring to Figs. 1 and 4 *a, b*, represent two rotatable crimping or corrugating members, by means of which a lip *c* on a channeled inner sole *d* of substantially non-compressible material, may be provided with crimps or corrugations 10, see Fig. 6, which are materially deeper at the free edge of the lip *c* and taper to nothing near the bottom of said lip. For this purpose the rotatable crimping member *a* is provided with a beveled circumference having teeth 12, which are of greater depth at one surface and taper or incline to substantially the circumferential edge of the other or opposite surface, whereby the member *a* is provided on its periphery with tapering teeth of substantially no depth at one surface and of maximum depth at the other or opposite 60 surface.

The crimping member *b* is provided with similar teeth 14 which are of greatest depth at the upper surface, and taper to nothing at the lower surface.

75 The members *a, b*, have their teeth intermeshed, with sufficient space left between the outer edge of a tooth on one member and the bottom wall 15 of a tooth of the other member, for the passage of the lip *c*, which is fed between the members *a, b* and is provided with crimps or corrugations 10, see Fig. 6, which are of greatest depth and width at the upper or free edge of the lip, and taper or diminish to nothing at or near the bottom of the lip, where the latter joins the body portion of the inner sole.

In Fig. 1, the members *a, b*, are shown as arranged in the same plane and are rotated in unison. To this end, the member *a* is fast 90 on a shaft 20 having bearings in a vertical head 21 of a stationary framework 22, and provided with a gear 23, which meshes with a gear 24 on a shaft 25, on which the member *b* is mounted. The shaft 25 has bearings 95 in a block 26, which is mounted to turn on pivots 27, see Fig. 2, carried by the stationary framework of the machine. The block 26 is yieldingly held up against the head 21 by springs 29, which encircle rods 30 extended loosely through the lower end of the block 26 and secured to the head 21 of the framework. The springs 29 allow the block 100 26 to be moved backward on its pivots 27,

to compensate for different thicknesses in the lip *c* passing between the crimping members *a*, *b*.

The shaft 20 may be driven in any suitable manner, and is shown as provided with a bevel gear 32, which meshes with a bevel gear 33 on a main or driving shaft 34, mounted in bearings in the stationary framework of the machine and provided as herein shown with a driving pulley 35.

The shaft 25 is extended through an elongated slot 36 in a horizontal portion 37 of the stationary frame, which is secured to a suitable base 38.

Provision is made for supporting the inner sole, while the lip is being crimped by the members *a*, *b*, and for this purpose, a disk 40 having a substantially flat upper surface is loose on a rod 41, which is extended down through the base 38 and is designed to be connected with a treadle, not shown, by means of which the work supporting disk 40 may be lowered away from the crimping members *a*, *b*, to place the inner sole in position to have its lip *c* crimped, and to remove the inner sole from the machine after the lip has been crimped.

The work support or disk 40 is moved upwardly with the rod 41 by a spring 42, which encircles the rod 41 between a hanger 43 and a disk 44 fast on said rod. The spring 42 acts to press the work or inner sole up against the rotatable member *b*. The downward movement of the work support or disk 40 is limited by a suitable stop, shown as the top of the base 38, and the latter may have erected upon it a post 46 to serve as an auxiliary support for the inner sole.

The member *b* may be positioned with relation to the member *a* to adjust the said members for lips of different thickness, by a threaded rod 50, which extends through the head 21 of the stationary framework, and acts as a stop to limit the movement of the block 26 under the influence of the springs 30.

The lip *c* is normally flat on the inner sole *d*, and provision is made for turning the same into a position substantially at right angles thereto, so that the lip may be properly presented to the crimping members *a*, *b*, and for this purpose I have provided a wire rod 51, which is fastened as by a screw 52 or otherwise, to a plate 53 attached to the head 21 of the framework, said wire rod having a curved arm 54, which is beveled and has its free end arranged in close proximity to the members *a*, *b*, at the point where they intermesh.

In operation, the inner sole *d* with the lip *c* in its normal or flat position is placed upon the work support 40 after the latter has been lowered by the operator, and when placed thereon so that one end of the lip is in position to be engaged by the turning de-

vice 51, the operator releases the treadle, and allows the spring 42 to move the work support upwardly, until the inner sole is engaged with the lower surface of the member *b*, and when this takes place the inner sole is fed by the rotation of the member *b* and the work support 40, and the turned portion of the lip is passed between the crimping members *a*, *b*, which crimp or corrugate the lip after the manner shown in Fig. 6. After the lip has been crimped, the work support 40 is lowered, to permit the crimped inner sole to be removed and an uncrimped inner sole to be placed on the work support. The crimping members *a*, *b*, are shown in Figs. 1 and 3 as arranged in the same horizontal plane, but it is not desired to limit the invention in this respect, as they may be arranged in planes substantially at right angles to each other, as represented in Fig. 5, and when so arranged, the lip *c* is given a greater inclination beyond a position substantially at right angles to the inner sole. When the crimping members *a*, *b*, are arranged as shown in Fig. 5, the hub of the member *b* is made large enough to engage the inner sole to feed the same.

I have herein shown one construction of machine embodying this invention, but it is not desired to limit the invention to the particular construction shown.

Claims:

1. In a machine of the character described, in combination, rotatable crimping members provided with substantially parallel faces, one of which is capable of engaging the work, and having on their circumferences intermeshing teeth of a maximum depth near one face of said members and tapering to substantially nothing near the work-engaging face of said members, and means for rotating said members.

2. In a machine of the character described, in combination, rotatable crimping members provided with substantially parallel faces, one of which is capable of engaging the work and having on their circumferences intermeshing teeth of maximum depth near one face of said members and tapering to substantially nothing near the work-engaging surface of said members, means for rotating said members, a work support located below the said members, and means to raise and lower said work support.

3. In a machine of the character described, in combination, a rotatable crimping member having a face capable of engaging the work and having a circumference at an acute angle to said face and provided with teeth of maximum depth at a point removed from said face and tapering to substantially nothing toward said face, and a coöperating rotatable crimping member having its circumference provided with tapering teeth with the portion of maximum depth coöperating

with the maximum depth of the teeth on the circumference of the first-mentioned member.

4. In a machine of the character described, 5 in combination, a rotatable crimping member having its circumference provided with teeth and having a face with which the work can contact on opposite sides of the center of said face at the same time, said teeth being 10 of maximum depth at a point removed from said face and tapering to substantially nothing toward said face, and a coöperating rotatable crimping member having tapering teeth on its circumference with the portion 15 of maximum depth coöperating with the maximum depth of the teeth on the circumference of the first-mentioned member.

5. In a machine of the character described, 20 in combination, a rotatable crimping member having a face capable of being applied to the work to make contact therewith on

opposite sides of its center, and having its circumference provided with teeth of maximum depth at a point removed from said face and tapering to substantially nothing 25 toward said face, a shaft on which said member is mounted to rotate therewith and to leave said face free to be applied to the work to make contact therewith on opposite sides of the center of said member, and a 30 coöperating rotatable crimping member having its circumference provided with tapering teeth with the portion of maximum depth coöperating with the maximum depth of the teeth of the first-mentioned member. 35

In testimony whereof, I have signed my name to this specification in the presence of two subscribing witnesses.
